(57) **CLAIM**

The ornamental design for a display screen with graphical user interface, as shown and described.

DESCRIPTION

FIG. 1 is a front view of a display screen with graphical user interface showing the new design; and,
FIG. 2 is an enlarged view of the graphical user interface of FIG. 1.

The broken line showing of the display screen in FIG. 1 is for the purpose of illustrating environmental structure and forms no part of the claimed design.
